UNITED STATES PATENT OFFICE.

DANIEL D. WHITNEY, OF CORNWALL, NEW YORK, ASSIGNOR TO THE WHITNEY COUPLING COMPANY, OF WHITINSVILLE, MASSACHUSETTS.

THILL-CO尤LING.

SPECIFICATION forming part of Letters Patent No. 415,180, dated November 12, 1889.

Application filed August 20, 1889. Serial No. 321,413. (No model.)

To all whom it may concern:

Be it known that I, DANIEL D. WHITNEY, of Cornwall, county of Orange, State of New York, have invented an Improvement in Thill-Couplings, of which the following description, in connection with the accompanying drawings, is a specification, like letters on the drawings representing like parts.

This invention has for its object to improve the construction of thill-couplings, whereby a strong, durable, and efficient coupling is produced, rattling is prevented, strain on the bolt lessened, and wear may be readily taken up.

In accordance with this invention the thill is pivoted by means of a bolt to a yoke which is provided with a clip or strap which embraces the cross bar or axle, and which is secured thereto in any usual or suitable manner. A holder or frame is provided, which is secured to the coupling by a nut or equivalent, said holder or frame receiving a concaved block in the concavity of which the hub of the thill rests. The concaved block herein preferred consists of two parts—viz., a bearing-block, which is provided on its concaved face with anti-friction material, as graphite, and in the concavity of which the hub of the thill rests to thereby wear or move on the anti-friction or graphite bearing-surface, and a yielding cushion upon which the bearing-block rests—yet the block may be made in one piece of yielding or elastic material. The said block is pressed into contact with the hub of the thill more or less, as desired, by adjusting its holder or frame.

Figure 1 shows in longitudinal section and partial elevation a thill-coupling embodying this invention; Fig. 2, a right-hand end view of the thill-coupling shown in Fig. 1, and Fig. 3 a modification to be referred to.

The thill *a*, or plate attached to the thill proper, has a hub *a'*, through which passes a bolt *a''*, serving as a pivot for the thill, said bolt also passing through ears *a³ a⁴* of a yoke, to the back or crown of which is attached a clip or strap *b*, which passes over and embraces the cross bar or axle *c*. The clip or strap *b* has screw-threaded ends *b'* project-

cross-bar *c*, and a cross-bar *d*, having suitable holes through it, is placed upon the screw-threaded ends of the strap *b*, and nuts *d⁵* are thereafter turned upon said screw-threaded ends to securely clamp the coupling to the cross-bar or axle. The yoke having the ears *a³ a⁴* and the strap *b* having the screw-threaded ends *b'* are herein shown as made of a single piece of metal.

As represented in Figs. 1 and 2, a holder or frame is employed, comprising the bottom portion *e³*, side portions *e⁴*, and the back portion *e⁵*, extended upward between the hub *a'* and the yoke, the said back portion terminating in a screw-threaded projection *e⁶*. The bottom portion *e³*, sides *e⁴*, and back *e⁵* constitute a box-like structure for holding a yielding cushion *e²* and a bearing-block *e*. The yielding cushion *e²* is made of rubber and the bearing-block of metal. The bearing-block has on its under side a lip *e'*, which assists in holding the yielding cushion in place.

The holder or frame is held in position by means of a cross-bar *e⁷*, having a hole through it to receive the shank of the screw-threaded portion *e⁶*, and extended laterally to bear upon the ears or lugs *a³ a⁴* of the yoke, and a nut *e⁸* is turned upon said screw-threaded portion *e⁶*. As a lock for the nut I have herein shown the cross-bar *e⁷* as recessed or concaved to receive a convexed or projecting side or face of the nut *e⁸*, (see Fig. 2,) so that as the nut is turned the projecting portion or portions thereof will pass over the projecting portions of the cross-bar, the cushion *e²* yielding to permit such movement, and the said projections will thereafter enter the recess in the cross-bar. This form of lock-nut will not readily be displaced. The upper face of the bearing-block is concaved, and is also recessed to receive anti-friction material, as graphite, so that the hub *a'* of the thill may come in direct contact with said material.

The bearing-block *e* and yielding cushion *e²* may be made in one piece, of yielding material, as represented in Fig. 3, and still a very efficient and durable thill-coupling produced.

It will be seen that the holder or frame may be raised and lowered by turning the nut *e⁸*, 100

and thereby increasing or decreasing the friction between the hub and block, said adjustment also compensating for wear. By this form of coupling the thill may be held in any 5 position desired, and when moved on its pivot will move under whatever degree of tension it may be subjected to by the turning of the nut e^8 .

By means of the holder or frame, the block 10 carried by it, and the cross bar and nut the block is raised vertically against a fixed point, as the lugs or ears serve as a purchase or seat for the cross-bar, so that the only adjustment or movement of the block is vertical; and as 15 the object to be raised is at one side of the seat or purchase the tendency is to draw the hub toward the axle, and thereby lessen the strain on the bolt.

I claim—

20 1. A thill-coupling comprising as a co-operative part of it a bearing-block, as e , having a concave upper surface, and a lip e' formed on its under side, a yielding cushion e^2 , upon which the said block rests, and which 25 is retained in place by the lip e' , a vertically-adjustable holder or frame for the block and cushion, having a base e^3 , side portions e^4 , and the upwardly-extended back portion e^5 , and 30 means for vertically adjusting the said holder with relation to the yoke, substantially as described.

2. In a thill-coupling comprising a yoke to which the thill is attached and means for attaching said yoke to the cross-bar or axle, the 35 combination, with the hub a of the thill, of the bearing-block e , having on its surface anti-friction material, a yielding cushion for said bearing-block, the cross-bar e^7 , having an opening therein, and a holder or frame provided with an upwardly-extended back portion e^5 , having a screw-threaded shank, and adapted to enter the opening in said cross-bar and be retained therein by a suitable nut on its shank, substantially as described.

40 3. In a thill-coupling, the yoke to which the thill is pivoted and means for attaching said yoke to the cross-bar or axle, combined with the concaved metallic bearing-block for the hub of the thill, the concaved or contacting surface of which is provided with anti-friction material, a yielding cushion, on which the said bearing-block rests, and a holder or

frame containing said bearing-block and cushion and made vertically adjustable with relation to the yoke, substantially as described.

4. In a thill-coupling, the yoke to which the thill is attached and means, substantially as described, for attaching said yoke to the cross-bar or axle, combined with the bearing-block for the thill, the yielding cushion e^2 , the holder or frame, the cross-bar e^7 recessed as described, and the lock-nut e^8 , having a projection to enter said recess in the cross-bar e^7 , substantially as and for the purpose 65 set forth.

5. In a thill-coupling, the yoke to which the thill is attached and means, substantially as described, for attaching said yoke to the cross-bar or axle, combined with a holder or frame 70 consisting of a base part located below the hub of the thill, and a shank rising vertically between the hub of the thill and yoke, a block carried by said holder or frame, the cross-bar e^7 , and a nut turned on the shank of the 75 holder, substantially as described.

6. In a thill-coupling, the yoke to which the thill is attached and means, substantially as described, for attaching said yoke to the cross-bar or axle, combined with a holder or frame, 80 a block carried by it adapted to be pressed in contact with the hub of the thill, a cross-bar bearing on the yoke through which the shank of the said holder or frame passes, and a nut or equivalent for the said holder or 85 frame, substantially as described.

7. In a thill-coupling, the yoke to which the thill is attached and means, substantially as described, for attaching said yoke to the cross-bar or axle, combined with a block for the 90 thill, a holder or frame for the block, a cross-bar bearing on the yoke through which the shank of the holder or frame passes, and a lock-nut, the said cross-bar and lock-nut having one a recess and the other a projection 95 to enter the recess, substantially as and for the purposes set forth.

In testimony whereof I have signed my name to this specification in the presence of two subscribing witnesses.

DANIEL D. WHITNEY.
